BENTON A. BASS AND ROLLIN D. OSGOOD, OF BIRMINGHAM, ALABAMA.

RAIL-Straightening Mill.

1,071,861.

Specification of Letters Patent.

Patented Sept. 2, 1913.

Application filed December 30, 1912. Serial No. 739,372.

To all whom it may concern:

Be it known that we, BENTON A. BASS and ROLLIN D. OSGOOD, citizens of the United States of America, residing at Birmingham, in the county of Jefferson and State of Alabama, have invented certain new and useful Improvements in Rail-Straightening Mills, of which the following is a specification.

10 Our invention relates to an improved railroad-rail straightening machine comprising a series of lower rolls which operate alternately with reference to oppositely disposed pairs of top and side rolls, and the 15 objects of our improvement are, first, to straighten crooked rails by applying pressure upon the base and web of the rail at the same time; second, to straighten a rail with a crook near the end; third, to straighten 20 a twisted rail; and fourth, to reduce the injury done to a rail by the present methods where the rail is hammered or the fiber of the steel broken down.

We attain these objects by the mechanism 25 illustrated in the accompanying drawings, in which:—

Figure 1 is a top view of the entire machine. Fig. 2 is a side view of the same. Figs. 3^a, 3^b and 3^c are partial views showing 30 relative positions of different co-acting rolls in the machine. Fig. 4 is a vertical section of a part of the machine on the line 4—4 of Fig. 1. Fig. 5 is a top view of a part of the machine as it appears with the top roll 35 and housings removed on the line 5—5 of Fig. 4. Fig. 6 is a vertical view of part of the machine on the line 6—6 of Fig. 1. Fig. 7 is a horizontal view of the finishing end on the line 7—7 of Fig. 8, and Fig. 8 is a 40 vertical section of part of the machine on the line 8—8 of Fig. 1.

Similar numerals refer to similar parts throughout the several views.

The machine, in its preferred embodiment, comprises the base 1 upon which a series of housings 2 are bolted and each disposed midway between bearings 3 which are integral with the base and serve to support rolls 4 and 4^a. These rolls have grooves 5 and 5^a turned in their centers to fit the head of a rail. From the rail receiving end of the machine, which is at the right of Fig. 1, the spaces between the centers of adjacent bottom rolls gradually decrease until 55 the distance between the centers of the last

two bottom rolls 4^a is as short as is practical from a construction point, it being noted that the diameter of the rolls 4^a is made less than that of rolls 4 to bring their centers sufficiently close and still provide space for the interposed top roll hereinafter described. These bottom rolls are set with the transverse centers of their grooves 5 in a straight line and with the bottoms of the grooves lying in the same horizontal plane. With the exception of the last pair of rolls 4^a, these bottom rolls may be lined up by means of hexagon bushings 6 (see Fig. 7). Each of the bottom rolls is driven by a gear 7 on an extension of its trunnion, which gears each mesh with a bevel gear 8 on a line shaft 9, which is mounted in suitable bearings 10 and driven by a train of gears 11, 12, 13 and 14 from the motor 15. We provide bearings 10^a for the trunnion adjacent to the gears 7 and mount these bearings on the base 1 at one side thereof. Half way between the axial centers of each pair of bottom rolls and equi-distant from the longitudinal center line of their grooves 5 are set two side rolls 16 which are mounted on vertical axes 18 which, except for the rolls 4^a, are formed integral with blocks 17. These blocks are transversely adjustable on a raised central portion 19 of the base 1 by means of a screw shaft 20 mounted against axial movement in bearings 21 fixed on the base. These shafts 20 are controlled by hand wheels 22 mounted on one end of the shaft which projects toward the operator's side of the machine to bring the wheel into convenient position. The threaded portion of the shaft is enlarged and its ends engage the bearings 21 to hold the screw against longitudinal movement. The blocks 17 have reversely threaded transverse openings to receive the screw which has its threads which engage one block given a reverse pitch to the threads which engage the opposite block so that by turning the hand wheel 22 the blocks which support a co-acting pair of rolls 16 may be drawn together or separated to relatively adjust the rolls. To maintain the axes 18 of the rolls 16 and the bearings 21 in transverse alignment, the blocks 17 and bearings have bottom tongues 23 which work in transverse grooves 24 in the raised central portion 19 of the base. The rolls 4 are set down in openings in this portion 19 which is raised slightly above the 110

side portions of the bed that support the housings 2, and extend lengthwise of the bed to but not under the bearings for the last set of rolls 4^a.

Above each pair of side rolls 16 is a top roll 25 with its axis in the same vertical transverse plane with the axes of its respective side rolls. These top rolls revolve in bearings 26 which slide in the housings 2 and are adjusted up and down by means of screws 27 which are screwed down through suitable threaded openings in the tops of the housings 2 and have their upper squared ends in sliding engagement with bevel gears 28 which turn on a suitable faced bearing on the top of the housing. The gears 28 for adjusting the bearings at each end of a roll are simultaneously and equally adjusted by means of gears 29 mounted on a cross shaft 30, which turns in bearings 31 bolted to the inner sides of the tops of housings. We provide a hand wheel 32 for each shaft near the operator's side of the machine. The housings at their upper ends are braced together by cross rods 33 which have their outer ends reduced so that the shoulders thus formed will engage the inner sides of the housing while the reduced ends pass through suitable openings in the housings 30 and have nuts or heads 34 thereon to hold the housings together. The lower ends of the adjusting screws 27 are turned smooth and grooved to receive transverse pins 35 which pass through the bearings and groove 36 and hold the parts assembled. The rolls 25 have their central faces flattened and taper to each side where they engage a short coiled spring 36 which surrounds the trunnions of the roll and are interposed between it and its bearing 26, thus permitting the roll to have a slight axial play in its bearings.

In view of the crowded condition of the rolls 4^a at the delivery end of the machine, where, if possible, the last pair are brought with their centers within twelve inches of each other, we have found it necessary to modify the construction of the several rolls and their mountings somewhat.

Referring to Fig. 1, it will be seen that the housings for the top rolls 25^a, which are shorter than rolls 25, are brought closer together and the bed of the machine correspondingly narrowed. In Fig. 2, it will be seen that the housings are not so high for the rolls 25^a as they have a less diameter than rolls 25 and are preferably turned without a taper toward the ends. The gears 7 and 8 which drive rolls 4^a are designed to drive them with the same surface speed as that of rolls 4. The housing 2 for the first roll 25^a is similar to housing 2 only smaller, and the bearing for the first roll 4^a is also similar to that for the rolls 4, but the manner of mounting the first two pairs of rolls is illustrated in Figs. 7 and 8 and differs

somewhat from the mounting of rolls 16. Here each roll 16^a is mounted on a separate bearing block 37 which has a bottom T-head tongue 38 that slides in a correspondingly shaped transverse groove in the bed 1. We use set screws 39 which are screwed through bosses 40 in the housings 2^a and are held in rotatable engagement with the blocks 37 by pins 35^a which work in grooves in the screws. Hand wheels 41 are used to turn the screws 39. These hand wheels, which are arranged on both sides of the mill, will permit a pair of the rolls 4^a to be adjusted to either side of the center line to give the rail a sweep or curve to one side or the other and this curve may be purposely left in the rail when it is desired to deliver a finished rail with a determined side curve, or the side sweep thus given the rail may be taken out by the last pair or pairs of side rolls and bottom rolls. The rolls 16^a turn on stub shafts 18^a integral with 37 and may have their inner and bottom bearing faces suitably lined with antifriction metal. It will be noted that the rolls 16 and 16^a are left free to adjust themselves vertically on their respective stub shafts, which is important in that it permits the side guide rolls, when engaged by the rail head or base, to adjust themselves in a vertical line and follow the rail while it is being straightened by the action of the top and bottom rolls. The bottom rolls 4^a do not have the taper sides to their rail head grooves 5^a which are shallower than grooves 5. The rods 33 and nuts 34 are omitted for the sake of clearness from Figs. 1 and 2.

In the case of the last or finishing rolls 4^a, we provide a common bearing for these in the form of two adjustable blocks 42 which are set in a depression at the end of the base 1 which is formed by stopping the raised intermediate portion 19 of the base and providing a flat base 44 (Fig. 8) which has a transverse alining slot to receive the tongues 45 in the blocks. Set screws 39 are connected to and act to adjust the blocks 42 like the blocks 37, both of which blocks have integral stub shafts 18^a for the side rolls 16^a which are preferably left free thereon for vertical adjustment in the same manner as the rolls 16. As the last two top rolls 25^a are so close together, we mount them in a double housing 46 in which are two slots to receive the bearing blocks 26. It will be noted that these bearing blocks 26 have flanges at their inner ends which engage the side walls of the groove and hold the blocks against outward movement. To remove these blocks it is only necessary to loosen the screw bolts 46^a (Fig. 4), which hold the housings 2, 2^a and 46 and move them outwardly. The several adjustable blocks 17 which support the side rolls 16 are provided with upwardly inclined guides 47 (Figs. 5 and 6), and it will be noted in Fig. 2 that we

illustrate delivering and receiving rolls 48 and 49, respectively, for delivering the rail 50 to and receiving it from the mill.

To feed the rail into the mill we provide 5 a pinch roll 51 disposed above the first bottom roll 4. A gear wheel 52 turns with this roll 4 and meshes with a similar gear 53 fixed on a trunnion of the pinch roll. The bearing blocks for the pinch roll 51 are 10 pressed downwardly yieldingly by springs 54 interposed between them and screw blocks 55 which slide in housings 56. Separate hand wheels 57 are used to adjust the screw blocks and regulate the tension on the 15 springs which hold the pinch roll to its work.

In operation, a rail 50 to be straightened, should be first curved in a rail curving machine in any desirable manner so that it 20 comes to the delivery rolls 48 curved with its head on a shorter radius than its base (see Fig. 6). The rail as thus curved is turned by any suitable mechanism so as to bring its head in the under or low position 25 and it is then introduced between the pinch roll 51 and the first roll 4, the head of the rail entering the groove 5 in the latter roll. As stated, when it is desired to put a side sweep in the rail or to give it a side curvature and then take it out, this can be accomplished by the adjustment of the end pairs of side rolls 16^a to one side or the other of the longitudinal center line of the mill. As the pinch rolls draw the rail into the 30 mill, its downwardly curving forward end will strike the guides 47, which will steer its head between the first pair of side rolls 16 and under the first top roll 25. The head of the rail will engage the under sides of 35 the rolls 16 and the latter are free to rise with it while holding it in the center line of travel. The rail then passes on until its head enters the groove 5 in the second bottom roll 4, whereupon, due to its arch, pressure is brought to bear on its base flange by roll 25 and at the same time one or the other of the side rolls 16 will apply pressure on a side of the rail. The top roll 25 presses the front end of the rail downwardly 40 against and between the first two rolls 4 which, at the time are supporting it. This operation is repeated as the head of the rail travels from one to the other of the rolls 4 and 4^a in traversing the mill, it being noted 45 that the rolls 4, 25 and 16, at the entrance are set so as to take only a part of the bend out of the rail, as shown in Fig. 3^a, where it is seen they have a wide operating clearance which is gradually reduced as seen in Figs. 50 3^b and 3^c until at the finishing end the clearance disappears and the rail is gripped on all sides by the rolls and held straight so that all distortion is taken out except within six inches of the end of the rail. By this 55 means the rail is gradually bent in stages

without any violent straining or hammering until it is straight. The most important point to be noted however is that in thus gradually straightening the rail, side and top rolls are arranged to co-act on the rail at the same time and exert their straightening force in the same transverse plane of the rail which thus has its twists or curves in both vertical and horizontal planes treated simultaneously and gradually removed, 70 and when this is the case the rail will remain in the position to which it is bent after each operation without having a tendency to spring out of line in one direction when it is straightened in another, as occurs in the present practice where the rail is treated in different mills for removing its curvature in different planes. Since the steel from which the rails are rolled will have different percentages of carbon, our 75 mill is made flexible so that we can vary the amount of pressure required to straighten a rail. A return table may be provided adjacent to the mill so that in passing the first rail of heat through the mill, if it is not straightened in its first passage it may be returned to the delivery rolls 48 and again passed through the mill after the rolls therein have been readjusted. When the 80 mill has been thus adjusted for the rail of 85 any one heat, the other rails of that heat, or rails in which the steel has a like carbon content, can generally be rolled without requiring further adjustment.

Though we refer to the side and top rolls as laterally and vertically acting rolls, it is obvious that such terms are relative and that the essential feature is that what we term the "top roll" shall exert its straightening force in a plane substantially at right angles to the plane in which the so called "side rolls" act, whatever that plane may be. In like manner, though we frequently refer in the appended claims to the so called "top" and "side" rolls acting in the same transverse vertical plane, we mean by this that these co-acting rolls shall be so situated relatively that they apply to a given transverse cross-section of the rail simultaneously, straightening forces from the several directions necessary to straighten the rail, and in order to minimize the shock to the fiber of the metal, such straightening forces are applied gradually.

To apply the straightening forces in a given transverse cross section of the rail, it is preferable that the rolls be arranged in the same vertical plane, but obviously if they are in substantially the same plane, the results desired will be obtained.

Though we prefer to adjust the top rolls vertically and to provide the bottom rolls with the alining rail receiving grooves, obviously this arrangement may be reversed and the bottom rolls adjusted upwardly 130

while the upper rolls carry the grooves. In like manner the grooves may be designed to fit the base or head of the rail, the latter being preferable.

5 We prefer to arrange the mill with a successive series of straightening mechanisms which gradually straighten the rail, but it will be understood that our invention will cover a greater or less number of such mechanisms than that shown or may even be embodied in a single mechanism comprising a pair of bottom grooved rolls and an intermediate mechanism for vertically and laterally straightening the rails.

10 Having thus described our invention, what we claim as new and desire to secure by Letters Patent, is:—

15 1. In a rail straightening mill, a series of spaced guide rolls having alining central grooves adapted to receive the rail, a series of vertically acting straightening rolls interposed between and co-acting with adjacent pairs of guide rolls, and laterally acting straightening rolls disposed in a transverse vertical plane with each of said vertically acting straightening rolls, substantially as described.

20 2. In a rail straightening mill, a series of spaced guide rolls having alining grooves adapted to receive the rail, and a series of rail straightening mechanisms interposed between the guide rolls, each of said mechanisms comprising means adapted to apply to the rail in substantially the same transverse vertical plane and contemporaneously a vertical and from either direction a lateral straightening force.

25 3. In a rail straightening mill, a series of spaced bottom rolls having alining grooves adapted to receive the rail head, and a series of rail straightening mechanisms interposed between the bottom rolls, each of said mechanisms comprising three rolls adapted to simultaneously apply a downward and a lateral straightening force to the rail in substantially the same transverse plane.

30 4. In a rail straightening mill, a series of spaced bottom rolls having alining grooves adapted to receive the rail head, a series of rail straightening mechanisms one of which is interposed between each pair of bottom rolls, each of said mechanisms comprising relatively adjustable rolls arranged in the same transverse vertical plane and adapted to simultaneously apply a downward and a lateral straightening force from either side to the rail, and means to adjust said mechanisms to take the curvature out of the rail gradually in steps as it moves through the mill.

35 5. In a mill for straightening rails which are curved with their heads on the shortest radius, a series of bottom rolls having alining grooves adapted to receive the rail head and which are spaced decreasing distances

apart toward the delivery end of the mill, a series of top straightening rolls, one of which is spaced equi-distantly between each pair of bottom rolls, means to adjustably mount said top rolls, a series of pairs of side straightening rolls, there being one pair between each pair of bottom rolls, and means to laterally adjust the units of each pair of side rolls.

40 6. In a straightening mill for rails, means to feed the rail into the mill, a series of bottom rolls having alining grooves adapted to receive the rail, a series of rail straightening mechanisms, one of which is interposed between each pair of bottom rolls, said mechanisms comprising each a vertically adjustable top roll and a pair of laterally adjustable side rolls, means to adjust said top and side rolls, and inclined guides to direct the forward end of the rail between the successive pairs of side rolls, substantially as described.

45 7. In a rail straightening mill, a series of horizontally disposed guide rolls for the rail which have alining grooves adapted to receive the rail, a series of horizontally disposed straightening rolls spaced from and arranged in staggered relation to the guide rolls said straightening rolls being arranged with their rail engaging faces gradually approaching the horizontal plane of the rail supporting surfaces of the guide rolls toward the discharge end of the mill, and adjustable rolls to apply lateral straightening pressure to the rail in substantially the same transverse vertical plane that vertical straightening pressure is applied by said horizontal straightening rolls, substantially as described.

50 8. In a straightening mill for rails, a base, a series of vertical housings mounted thereon and which are spaced gradually decreasing distances apart toward the discharge end of the mill, top straightening rolls, and means to vertically adjustably mount one in each opposite pair of bearings, side straightening rolls, a pair of which is disposed under each top roll, means to laterally adjust the units of each pair of side rolls, a lining means to guide said side rolls in their adjustments, and bottom guide rolls which receive the rail and are spaced on gradually decreasing centers equi-distantly between each pair of top rolls, said guide rolls having rail receiving grooves which aline throughout the mill, substantially as described.

55 9. In a rail straightening mill, pinch rolls to feed the rail into the mill, bottom guide rolls which have alining grooves to receive the rail and which are spaced on gradually decreasing centers toward the discharge end of the mill, adjustable top and side rolls which simultaneously engage and in conjunction with said guide rolls exert simul-

taneously both vertical and lateral straightening force to the rail between each pair of bottom rolls, the finishing bottom and side rolls having common adjustable bearings, 5 substantially as described.

10. In a rail straightening mill having closely associated grooved guide rolls at its discharge end and pairs of vertically disposed co-acting rolls which act laterally on the rail, there being a pair of such rolls disposed between each adjacent pair of guide rolls, means for mounting a pair of laterally acting rolls which comprise bearing blocks for a pair of guide rolls, which blocks are 15 relatively adjustable, bearings carried by said blocks for the pair of laterally acting rolls disposed between the guide rolls which are mounted in said bearing blocks, means to hold said guide rolls in alinement independently of the adjustments of their said bearing blocks, and means to adjust said blocks, substantially as described.

11. In a rail straightening mill, a series of bottom rolls having rail receiving grooves 25 with their rail supporting surfaces in alinement in a horizontal plane, said rolls being spaced on gradually decreasing centers toward the discharge end of the mill, a top and a pair of side straightening rolls interposed between and co-acting with each pair of bottom rolls, said top rolls as they approach the discharge end of the mill being set gradually closer to the said plane of said grooves in the bottom rolls, and the units of 30 each pair of said rolls being set gradually closer together toward the discharge end mill, substantially as described.

12. In a rail straightening mill, means to pass a rail to be straightened therethrough, 40 and a straightening mechanism to act on the rail comprising a pair of spaced rolls grooved to receive the rail to be straightened, a straightening roll having its axis parallel with the grooved rolls and disposed 45 between them, said latter rail acting to force the rail against the grooved rolls to straighten it in one longitudinal plane, and a pair of rolls which co-act with and are disposed between the said grooved rolls and in 50 substantially the same transverse plane with said straightening roll and which are spaced apart to receive between them the rail, said latter rolls acting to straighten the rail in a longitudinal plane at right angles to the 55 said first mentioned plane.

13. In a mill for straightening rails as they are passed therethrough, a pair of spaced rolls grooved to receive one side of the rail, a set of straightening rolls interposed substantially midway between the grooved rolls and comprising three rolls adapted to engage the other three sides of the rail in substantially the same transverse cross sectional plane, and means to adjust

said intermediate rolls to regulate their 65 pressure against the rail.

14. In a rail straightening mill, means to straighten the rail as it is passed therethrough, rolls grooved to receive one side of the rail, rail straightening mechanism interposed between said grooved rolls and comprising rolls adapted to engage the other three faces of the rail in substantially the same transverse cross sectional plane, adjustable bearings for said straightening rolls, 75 and means to adjust the straightening rolls which are adapted to engage the web of the rail to one side or the other of a center line of said grooved rolls, substantially as described. 80

15. In a rail straightening mill, roll mechanism to straighten the rail as it is passed through the mill, said mechanism comprising a series of spaced bottom rolls having alining grooves to receive the rail, 85 a series of roll mechanisms interposed between each pair of groove rolls and adapted to gradually apply straightening pressure to the rail in longitudinal planes at right angles to each other, finishing rolls comprising 90 a pair of side rolls which receive the rail between them, and means to adjust said side rolls to one side or the other to the center line of the grooves in the bottom rolls.

16. In a rail straightening mill comprising a series of spaced rolls having alining grooves to receive the rail, rail-straightening mechanisms interposed between each pair of grooved rolls which are arranged on gradually decreasing centers, the finishing 100 grooved and straightening rolls being closely assembled, and adjustable bearings for the finishing grooved rolls and upon which bearings the finishing straightening rolls are also mounted. 105

17. In a rail straightening mill, means to straighten the rail as it is passed therethrough, said means comprising closely associated finishing rolls comprising spaced grooved bottom rolls, a pair of side rolls 110 and top straightening rolls interposed between said pair of finishing grooved rolls, the final pair of grooved rolls having a common bearing block on each side, which blocks are relatively adjustable, and vertical 115 axes carried on said blocks upon which the final pair of side rolls are mounted, substantially as described.

18. In a rail straightening mill, a series of spaced guide rolls having alining grooves 120 adapted to receive the rail, rail straightening mechanisms interposed between each pair of guide rolls and comprising top and side rolls, means to adjust the top rolls of said mechanism up and down to apply pressure against the upper portion of the rail, and means to adjust the said rolls toward and from the center line of the grooves to 125

set said rolls to bear on the web and head of the rail to keep the line of the rail straight, said side rolls having axes upon which they are freely movable, as and for the purposes described.

19. In a rail straightening mill, a series of spaced guide rolls which have alining grooves to receive the rail to be straightened, inclined guides to direct the forward end of the rail into the grooves of successive rolls as the rail is passed through the mill, roller straightening mechanisms interposed between each pair of grooved rolls, each mechanism comprising vertically adjustable top and side rolls, and means to adjust said side rolls to and from each other, the rolls of each straightening mechanism being adapted to engage the rail in substantially the same transverse cross sectional plane.
20. In a rail straightening mill comprising grooved guide rolls disposed in the same plane and spaced on decreasing centers, of sets of top and laterally acting rolls, one of which sets is disposed between each adjacent set of guide rolls, means to mount the

final pair of guide rolls which are closely associated, said means comprising a frame, axes for said rolls which are reduced at their outer ends and mounted in said frame, and a common bearing block for the corresponding unreduced end portions of the axes of said rolls, which bearing blocks are relatively adjustable on said frame and are adapted to move toward and from each other about said axes, means to hold said blocks in adjusted positions, and bearings for the pair of laterally acting rolls which are disposed between the pair of guide rolls in question, which bearings are mounted on said blocks and adjustable therewith, substantially as described.

In testimony whereof we affix our signatures in presence of two witnesses.
